APPARATUS FOR BURNING LIQUID FUELS

Thomas J. Stephens, Brooklyn, N. Y.

Application June 22, 1933, Serial No. 677,049

1 Claim. (Cl. 158—73)

In the practice of burning liquid fuels it has been found difficult to produce complete combustion at the instant of starting the fire, and equally difficult to prevent an escape of some 5 quantity of unburned fuel at and following the instant of extinguishing the fire.

My invention relates to improvements in the method of and apparatus for burning hydro-carbon fuels, and specifically to the correlation 10 of essential steps preparatory to such burning in cases where a gaseous atomizing agent, such as air or steam is used in conjunction with an ignition agent.

The present invention pertains especially to a 15 method of and apparatus for feeding hydro-carbon fuel into a stream of air or steam having sufficient volume and flowing at sufficient velocity to atomize said fuel as fed, and to carry the atomized particles within a vehicular jet into the 20 combustion zone.

Under all conditions it is essential to cause 25 the fuel-laden jet to ignite immediately upon entering the combustion area, and it is especially important in some industries utilizing oil as a fuel to accomplish ignition and complete combustion without permitting any particle of unburned fuel to escape from the zone of combustion. A good example of the requirement is to be found in such operations as the baking 30 of foods and roasting of coffee in ovens heated by oil fires under circumstances such that the products of combustion from the fire envelop the foods being baked or coffee being roasted. In such operations as these if the slightest amount 35 of fuel escapes from the combustion chamber unburned, the product of the oven will be proportionately injured, the commercial value of such products being based largely upon the delicacy of their flavor or aroma which if contaminated by unburned fuel must inevitably be injured or wholly destroyed.

In the operation of an oil fire the critical stages, or those stages of operation in which completeness of combustion is most difficult to attain, 45 are found in starting and in extinguishing the fire. As evidence of this fact city smoke prevention ordinances usually provide for a certain number of minutes after starting a fire during which the ordinance is not to be effective, in 50 recognition of the difficulty encountered in starting a fire without production of smoke.

With the foregoing in mind it is the purpose 55 of the present invention to provide a method of relatively simple steps arranged in practicable sequence and a preferred form of mechanical de-

vice, for carrying out said method, of simple and inexpensive construction whereby, for starting a fire, ignition conditions are established in the zone of combustion and also atomization conditions are established, at the point of fuel admission to said zone, both in advance of the delivery of any fuel to the atomizing mechanism or the combustion zone; and whereby, for extinguishing the fire, ignition conditions in the zone of combustion and atomization conditions 10 in the atomizing mechanism both are maintained until after all delivery of fuel has ceased, thereby sweeping out and completely burning the last particle of fuel before discontinuing either of said essential conditions.

Another object of my invention is to provide 15 a simple, practical and reliable method of, and apparatus for, regulating an oil fire to any desired volume of heat production and quality of flame within its range of capacity, and to thereafter readily extinguish and re-establish said fire 20 at will without changing or disturbing the said regulation, and without escape of the slightest particle of unburned fuel upon extinguishment or re-establishment of the fire.

Other objects of my invention will be apparent 25 from the detailed description thereof and an illustrative embodiment of an apparatus which constitutes only one of the means whereby the method of my invention may be effected.

In my method and by the device hereinafter 30 described, the liquid fuel and air are fed under pressure to a burner in their separate conduits and are joined by a third carrying the gas for ignition purposes, the jet for the gas being arranged adjacent the atomizing nozzle of the 35 burner and supplying a flame which is directed into the path of the atomizing jet projecting fuel from the nozzle. The three sources of fuel, air and a gas, respectively, are subjected to a 40 control at the burner, whereby first the volume of the gas flame is increased, thus establishing an ignition condition, then the air is released in the burner, thus establishing the atomizing condition, and finally the fuel itself is released 45 in the burner and is instantly atomized and ignited upon contact with the gas flame. To shut off the burner, the reverse steps take place, i. e. the fuel is the first to stop flowing, the air next, and finally the gas is cut down to a small pilot 50 flame; as a result, there is no possibility of any unatomized or unignited fuel being at any time discharged from the burner into the combustion chamber either when the fires are started or when they are extinguished.

In the drawings, Figure 1 is a side elevational view of the oil burning system according to my invention; Figure 2 is a substantially longitudinal sectional view of the burner and control therefor in full open position; Figure 3 is a substantially transverse sectional view of the oil passage taken on lines 3—3 of Figure 2; Figure 4 is a substantially transverse sectional view of the passage for the atomizing agent taken on lines 4—4 of Figure 10; Figure 5 is a transverse section of the oil nozzle and burner tip; and Figure 6 is a side elevational view of the oil feed nozzle.

Referring to the drawings and particularly to Figure 1, 10 denotes the fuel oil pump and air pump from which an oil line 11 and air line 12 lead off to supply a burner 13 which is directed into an enclosure forming the combustion zone A. Ignition is supplied by gas from a line 14 running from its source to a position adjacent 20 the other lines 11 and 12 at the burner.

The burner 13 in the present embodiment, comprises a metal casting having superposed cylindrical portions, the upper portion thereof housing the chamber for the fuel and air and the lower or under portion carrying the control elements for oil, air and ignition. The oil and gas lines 11 and 14, respectively, connect to the burner casting along the under side of the lower or control cylindrical portion, the air line 12 entering the burner at the side thereof and on a line intersecting the axis of the control portion.

The chamber constitutes an axial bore 15 having a threaded restricted opening 16 formed by a wall 17 within the chamber. The wall divides 35 the chamber into two sections, the rear section for oil communicating with the oil line 11 through a passage 18. The open or rear end of the latter section is internally threaded and is provided with a screw nut 19 having an enlarged central 40 flange 20 and externally threaded shank 21. The nut 19 is provided with an axial bore 22 which is threaded and receives the threaded sleeve 23 of a needle valve 24, the latter consisting of a spindle extending beyond the opposite ends of the nut 19, the inner end having a reduced portion 25 provided with tapered slits 26 through which the flow oil from the chamber is controlled or regulated. The outer end of the spindle carries a hand wheel 27 and a packing nut 28 encircling 50 the spindle is screwed down over the threaded shank 21.

The reduced end 25 of the spindle is adjustably projected into a bore 29 of a tubular member 30, which is threaded at its ends, one thereof being 55 screwed into the threaded restricted opening 16 in the chamber wall 17, while the opposite end carries a nozzle 31. The tube 30 carries the oil from the oil section of the chamber, past the needle valve 24 to the nozzle 31, the latter having 60 a shank 32, which is square in transverse section, and which tapers off at its free end, as illustrated particularly in Figures 5 and 6. The bore of the nozzle 31 also tapers down to a smaller opening at its delivery end. In order properly 65 to arrange the tubular member 30 in the air chamber, a collar 33 is provided at the end of the threads entering the restricted opening 16, so that the collar 33 seats against the wall 17. The reduced end 25 of the needle valve is ground 70 to have a sliding fit in the bore of the tubular member 30, as illustrated in Figure 2. The outer end of the air section of the chamber is increased in size and internally threaded to accommodate 75 the threaded shank of a nozzle tip 34, the latter having a bore 35, the diameter of which corre-

sponds to the length of the diagonal of the square shank of the nozzle 31, so that in operation the latter is always assured of perfect centering within the tip 34, the spaces between the flat faces of the nozzle 31 and wall of the bore 35 providing 5 air passages. The outer or delivery end of the tip 34 is tapered off short and provided with an orifice 36 of a size to surround the tip end nozzle 31, as shown in Figure 2.

Air is led into the air section of the chamber 10 through an angular passage 37 leading towards the control section of the burner casting from the inlet to the air line 12. The control elements for the oil, air and gas comprise a rotary valve spindle 38, which is in a single piece and 15 which turns on an axis parallel to the axis of the oil and air chamber and coincident with the axis of the lower cylindrical portion of the burner casting. On one end of the spindle 38 is a tapered section 39, which turns in a correspondingly tapered bore in the casting, and which is provided with a threaded tip 40 projecting beyond the delivery end of the burner casting to receive a washer 41 and nut 42. The opposite end of the spindle 38 is straight and projects through a packing chamber 43, which is formed by the continuation of 20 the tapered bore, a packing nut 44 being screwed into the chamber against the packing 45 which abuts a washer 46 at the inner end of the chamber. The outer end of the spindle 38 beyond 30 the packing nut 44, is keyed to a lever or handle 47, which is provided with a projection 48 adapted to engage stops 49 projecting from the wall of the casting at an effective angle of approximately 90° from each other. 35

The tapered portion of the spindle 38 is provided with a substantially transverse bore 50, which in the open position of the control valve registers and alines itself with the passage 18 for oil between the line 11 and oil section of 40 the chamber. Beyond the bore 50 and disposed in line with the angular air passage 37, the tapered valve section 39 is provided with a transverse slot 51 of sufficient length to more than embrace the ends of the vertical and lateral 45 portions of the air passage 18, so as to admit air through the passage 18 to the air section of the chamber before the valve is fully open, as illustrated in Figure 4.

Beyond the air slot 51, the spindle 38 is provided with a central bore 52, the outer end thereof being threaded to receive the stem 53 of a pilot burner 54 which is slightly offset with respect to the axis of bore 52 and projects beyond the delivery end of the burner tip 34. The inner 55 end of the bore 52 branches off at an angle and opens out onto the tapered surface of the spindle 38 through a slot 55 which is of a length approximately one quarter of the circumference, so that during its movement to open position of the 60 valve the gas will be permitted to flow to the pilot in full force before the oil begins to flow. The slot 55 communicates with the gas line 14 through a passage 56 leading therebetween and being disposed in the burner casting. In order 65 to maintain a small flow of gas to the pilot at all times, a bleed opening 57 is arranged in the casting between the valve and the passage 56, the opening 57 being provided with a screw valve 58 and opening into a circumferential groove 59 70 in the surface of the valve. A radial passage 60 in the valve completes the communication between the groove 59 and the central bore 52.

In operation, the rotary valve in its closed position brings the handle 47 in the position, illus- 75

trated in Figure 1, with the projection 48 abutting the lowermost stop 49. In this position the oil, air and gas passages in the burner are cut off. To open the control valve and set the burner in operation, the handle is turned upwardly towards the right until the projection abuts the upper stop 49. During rotary movement of the valve the first passage to open is that admitting gas in sufficient volume to increase the flame in the pilot 54, thus establishing an ignition condition; then the air passage is cleared and air under pressure is released to the burner, thus establishing the atomizing condition; and finally the fuel oil itself is released to the burner as the valve reaches its full open position, shown in Figure 2. The fuel reaching the burner at this stage is instantly atomized and ignited upon contact with the gas flame. To shut off the burner the reverse steps take place, i. e., the fuel shuts off first, the air next and finally the gas flame is cut down to a small pilot jet.

In industrial plants utilizing oil heated ovens or other heating compartments, it may be necessary to close off the burners from time to time and by means of the present method and the apparatus herein described it is only necessary to move the handle 47 and spindle 38 in a clockwise direction, to its initial position, to effect the operation, it being assured that there will be no after escape of unignited fuel. The device is so designed as to prevent such a possibility in that since the valves are opened in the following order,

gas for ignition, air for atomizing and oil to supply the fuel, the order of closing is just the reverse, i. e., the oil is cut off first, then the air sweeps the nozzle clear of fuel and stops, and finally after every particle of fuel has been consumed, the gas is turned low.

While I have described my method and a preferred apparatus for carrying out that method, it is understood that my invention is not to be limited to the particular details disclosed, the invention as to the method of being capable of performance by other apparatus and the apparatus being capable of various embodiments in addition to that illustrated.

Having now described my invention, what I claim and desire to secure by Letters Patent is:—

An atomizing liquid fuel burner comprising a housing including an atomizing nozzle, fuel and atomizing fluid passages communicating with said nozzle, a large gas passage, a small gas passage, a valve body extending through said housing and having an axial bore extending inwardly from the end near the nozzle in constant communication with said small passage, and ports controlling the flow of fuel and atomizing fluid to said nozzle and gas to said bore and operable when moved from closed to open position to sequentially open the large gas, atomizing fluid and fuel passages, and a pilot burner offset in respect to and in communication with said bore and carried by and movable with said valve body.

THOMAS J. STEPHENS.
